UNITED STATES PATENT OFFICE.

ISAMU HOSOI, OF TOCHIGI-KEN, JAPAN, ASSIGNOR OF ONE-HALF TO KAKUTARO TAKEL, OF TOKYO, JAPAN.

PHONOGRAPH.

Application filed February 18, 1925, Serial No. 10,078, and in Japan March 3, 1924.

This invention relates to improvements in phonographs of the type in which the revolution of the record disc is so controlled that the speed of a point thereof registering with the point of the phonographic needle is kept constant, and has for its object certain improvements in phonographs of the type specified according to which the controlling of the speed is effected by means, simple in construction and sound in operation.

According to the present invention a carriage is provided for the governor and the friction disc, which disc engages the underside of the turntable, and a track is provided upon which the carriage is adapted to move. A link member is provided forming a connection between the carriage and the tone arm, whereby the phonographic needle, as it traverses the record disc, causes the friction disc to be moved across the underside of the turntable with and at a point immediately beneath the said needle.

In the accompanying drawings:

Fig. 1 is a side view of the phonograph partly in section.

Figure 2 is a side elevation perpendicular to that in Figure 1.

In a body rotating at a constant angular speed, the linear speed of a point thereon varies according to the radial distance of that point from the center of rotation, and it is obvious that to obtain a constant linear speed of a particular point varying its radial distance, the angular speed must be suitably varied. For this reason, it will be readily understood that the angular or rotating speed of a record or a turntable must be gradually changed or increased as a phonographic needle passes across the record from the outside towards the center of the record disc.

Referring now to the drawing, a phonograph according to this invention comprises a casing 31, an ordinary spring motor 32, a turntable spindle 1, driven by said spring motor, a turntable 2 mounted thereon and rotated thereby and adapted to support a record disc 3 thereon and a sound box 17 associated with a phonographic needle 19, all of known construction. On the bottom of the casing 31 a track 4 is provided, which comprises a horizontally disposed plate hinged at one end and supported at the other end by means of a spring 5 or other 55 resilient means, as seen in Fig. 1. A carriage

6 is slidably mounted on the track 4. To facilitate the sliding motion of said carriage a number of antifriction balls 20 may be interposed between the underside of the carriage 6 and the track 4 in well known 60 manner. The carriage 6 has two upward stands, in the upper end of one stand being journaled a spindle 7. The spindle 7 has secured thereto a friction disc 8. At the other end of the spindle 7 is carried a toothed wheel 9. The friction disc 8 engages the underside of the turntable 2 at the point immediately beneath the contact point of the phonographic needle on the record disc and it is driven by said turntable during operation. This engaging contact is assured by means of the spring 5. Between the two stands of the carriage 6 a small shaft 10 is rotatably mounted. This shaft carries a toothed wheel 21 adapted to engage the 70 toothed wheel 9 whereby the shaft 10 is rotated. The shaft 10 serves as a governor shaft. The governor may be of any type, but in the drawings is shown a centrifugal governor comprising a collar 11 fixed to the 80 shaft 10, another collar 12 slidably mounted on the shaft, two spring blades 13 connecting the collars; which carry weights 14. The position of the slidable collar 12 is arrested in one direction by means of a brake 85 pad 16 mounted on a stand 15.

When the turntable 2 rotates, the friction disc 8 will be rotated at a linear rim speed equal to that of the record disc at the contact point of the needle on said record disc. The rotation of the friction disc 8 is controlled by the governor above described, to rotate at a constant angular and consequently peripheral speed. The result will be that the linear speed of the point of contact of the needle on the record disc is controlled by said governor and kept constant.

In order to keep the registering of the peripheral contact point of the friction disc 8 and the needle contact point on the record disc, a link member 18 is provided connecting the carriage 6 to the tone arm 17, which gradually varies its position in accordance with the centerward movement of the needle. The carriage 6 is driven by the movement of the tone arm 17 through the link member 18 and always keeps the friction disc 8 in contact with the underside of the turntable 2 at a point corresponding to the contact point of the needle 19 on the record disc.

With a mechanism according to this invention it will be obvious that the linear speed at the point of contact of the needle 19 with the record disc 3 is kept constant, independently of its radial distance, and a uniform speed of the record disc can be assured.

Moreover, as the point of the needle 19 and the engaging point of the friction disc 8 with the underside of the turntable 2 are always kept in register it is possible to use a record disc of a larger diameter than with phonographs of the well-known type, as the pressure of the needle is taken by the friction discs.

Having now particularly described and ascertained the nature of my said invention and in what manner the same is to be performed, I declare that what I claim is:

In a phonograph of the type specified, a

tone arm, a rotatable turntable, means for driving said turntable, a friction disc, a governor, a carriage adapted to carry said friction disc and said governor, a track for said carriage comprising a horizontally disposed plate hinged at one end and being supported at the other end by means of a spring whereby the friction disc is pressed against the under side of the turntable and a link member connecting said tone arm and said carriage whereby the carriage is moved by the phonographic needle as the latter traverses the record disc thereby causing the friction disc to be moved across the under side of the turntable with and at a point immediately beneath the needle.

In testimony whereof I affix my signature.

ISAMU HOSOI.
